(57) **CLAIM**

The ornamental design for a laundry sorter cart, as shown and described.

DESCRIPTION

FIG. 1 is a perspective view of a laundry sorter cart showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof with laundry bags installed therein;

FIG. 9 is an enlarged view of an indicated portion of FIG. 1; and,

FIG. 10 is an enlarged view of an indicated portion of FIG. 1.

The broken line portions of the laundry sorter cart in FIGS. 1-10 represent unclaimed portions of the claimed design and form no part thereof. The broken lines of the laundry bags in FIG. 8 illustrate unclaimed environment and forms no part of the claimed design. The dot-dash broken lines in FIGS. 1-5 and 8-10 represent unclaimed boundary lines and form no part of the claimed design.
